UNITED STATES PATENT OFFICE

LEONARD GERHARDT, OF BALTIMORE, MARYLAND, ASSIGNOR, BY MESNE ASSIGNMENTS, TO AMERICAN CAN COMPANY, OF NEW YORK, N. Y., A CORPORATION OF NEW JERSEY

LUNCH BOX

Application filed May 10, 1929. Serial No. 361,949.

My invention relates to receptacles of the general type in which the cover is so configured as to adapt it to snugly hold a thermos bottle or similar article while the body is adapted to hold sandwiches or other articles of food, the whole constituting a convenient lunch kit or box which will be useful and convenient to workmen, school children and others.

10 The principal object of the invention is the production of a lunch box or kit of the above character which shall be provided with a retaining member for detachably retaining a thermos bottle in position within the cover, said retaining member also acting as a pintle for hinged connecting the body of the box to the cover, thereby obviating the necessity of employing separate means for performing both functions and thus cheapening the cost of manufacture.

Other and further objects and advantages of the invention will appear from the following description taken in connection with the accompanying drawings in which:

25 Fig. 1 is a perspective view of a lunch box constructed in accordance with my invention without the thermos bottle.

Fig. 2 is a section taken through the lunch box showing the thermos bottle in position therein.

30 Fig. 3 is a section taken through a portion of the cover showing a portion of the retaining member before it has been snapped into locking position.

35 Referring in detail to the several figures of the drawings:

1 indicates the body of the box which is preferably metallic and rectangular in form and which is provided with ventilating openings 2 of any form. Said body is adapted to hold sandwiches or other articles of food. 3 indicates the cover the lower edge of which is adapted to interfit over the upper edge of the body. Said cover is preferably campanulate in cross-section whereby it may snugly receive a thermos bottle 4 within the rounded portion of the inner face thereof as indicated in Fig. 2.

40 The cover is provided with catches 5 of locking members adapted to detachably in-

terlock with corresponding members 6 on the body 1 for detachably holding the cover closed to the body. These locking members, however, may be of any suitable form and comprise no part of my invention. The body 55 1 is also provided with bearings 7 forming a part of the hinge connection between the cover and body. These bearings are formed by pressing out the metal from the body and then perforating the ends of said pressed-out portions in an obvious manner.

50 The horizontal pintle portions of a combined pintle member and retaining member are indicated at 8. These extend through the bearings 7 whereby the cover will be hinged 60 65 to the body. This combined pintle member and retaining member comprises a single piece of steel wire which is bent vertically from the pintle portions into two vertical portions 9 adapted to engage a side of the cover. The wire is then bent into two diagonal portions 10 which terminate in a horizontally disposed catch member 11. When the thermos bottle is placed in the cover as shown in Fig. 3 it may be securely 70 75 and detachably held therein by forcibly snapping the catch member 11 beneath a lug 12 pressed out of the metal on the cover. The pressure of the catch member beneath said lug will be resisted by the pressure of the 80 vertical portions 9 against a wall of the cover and the necessary spring and locking action will thus result.

85 To prevent binding of the vertical portions 9 against the back of the cover when the cover is closed and to obviate any difficulty in closing the cover, the back of the body has been provided with two grooves 13 each adapted to receive one of the vertical portions 9 of the combined pintle member and retaining 90 member. The top of the cover is also preferably provided with a pair of ears 14 adapted to have a flexible handle threaded therethrough (not shown) to provide a convenient means for carrying the receptacle.

95 What I claim as my invention is:

1. A lunch box comprising a body and a cover extending downward around the upper portion of the body and hinged to the body at the bottom edge of the cover, a re- 100

taining member adapted to support a container within the cover and having vertical portions hinged to the cover at the outer side of the body, said vertical portions extending from their hinge up between the edges of the body and cover and bearing against the outside of the body, whereby the retaining member is held in supporting position when the cover is closed, the said vertical portions being released by the opening of the cover.

2. A lunch box comprising a body having vertical grooves, and a cover extending downward around the upper portion of the body and hinged to the body at the bottom edge of the cover, a retaining member adapted to support a container within the cover and having vertical portions hinged to the cover at the outer side of the body, said vertical portions extending from their hinge up between the edges of the body and cover and bearing against the outside of the body in said grooves, whereby the retaining member is held from movement when the cover is closed, the said vertical portions being released by the opening of the cover.

Signed at Baltimore in the county of Baltimore and State of Maryland this 6th day of May A. D. 1929.

LEONARD GERHARDT.
